UNITED STATES PATENT OFFICE.

HARRY WOOD, OF NUTLEY, NEW JERSEY.

NON-REFILLABLE BOTTLE.

1,171,378.

Specification of Letters Patent. Patented Feb. 8, 1916.

Application filed December 12, 1913. Serial No. 806,312.

To all whom it may concern:

Be it known that I, HARRY Wood, a citizen of the United States, residing at Nutley, in the county of Essex and State of New Jersey, have invented certain new and useful Improvements in Non-Refillable Bottles; and I do hereby declare the following to be a full, clear, and exact description of the invention, such as will enable others skilled in the art to which it appertains to make and use the same.

My invention relates to improvements in bottles and has particular reference to that class of bottles known as non-fillable.

An important object of my invention is to provide a bottle of the character described which includes means arranged in the neck of the bottle and designed to permit the discharge of the contents from the bottle and at the same time act to prevent refilling of the bottle.

Another important object of the invention is to provide a bottle of the character described which is simple as to construction, reliable and efficient in operation and which may be cheaply manufactured.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts: Figure 1 is a section taken through the neck of a bottle and my improved means for permitting discharge and preventing refilling of the bottle, Fig. 2 is a top plan view of the guard member forming a part of the invention, Fig. 3 is a side elevation of the guard member, and Fig. 4 is a top plan view of the spring keeper employed for securing the device to a bottle neck.

Referring to the drawings forming a part of this specification and in which like numerals are employed to designate corresponding parts, the numeral 1 designates as an entirety a bottle having a short reduced neck 2 which is flanged peripherally upon its upper edge to produce a shoulder 3 for a purpose which will be later more fully described.

A cylindrical neck member 4 is adapted to be removably secured to the short neck 2 of the bottle 1 and is provided adjacent its inner end with an enlarged internally-annularly recess portion 5 in which a spring keeper designated 6 is adapted to be mounted. The spring keeper 6 is of the form such as illustrated in Fig. 4 of the drawings and consists of a metallic band having a plurality of angularly extending wings 7 thereon which are spaced from each other and provide a keeper which is substantially V-shaped in cross section. The ring is adapted to engage the side wall of the recess portion 5 of the neck 4 so that the wings 7 extend angularly with relation to the ring and adapted for engagement with the shoulder 3 formed on the neck 2 of the bottle 1. Thus it will be seen that the spring keeper 6 serves to immovably hold the neck 4 to the bottle 1 after having been disposed in the position such as hereinbefore described and illustrated in Fig. 1 in the drawings.

Mounted upon the short neck 2 of the bottle 1 is a valve seat designated 8 as an entirety. This valve seat 8 consists of a porcelain ring 10 mounted upon a suitable flexible packing ring 11 which is interposed between the member 10 and neck 2. This ring 10 is adapted to fit within an annular recess 12 formed in the neck 4. Mounted upon the ring 10 upon the upper surface thereof is an inverted cup shaped valve 13 and which is arranged to seat on the member 10. To hold the valve in closed position when the bottle is upright, I provide a weight 13'. This weight 13' is ball shape and may be formed of any suitable material.

A guard member 14 is mounted within the neck 4 and consists of a body portion of a circular contour being provided with an inverted frusto conical inner ball engaging seat 15. Formed integral with the periphery of the circular body portion of the guard member 14 are spaced legs 16 which support the device in the neck 4. The lower end of the legs 16 engage the upper face of the ring 10 while the upper ends of the legs 16 engage a shoulder 17 upon the under surface thereof which is formed in the neck 2 by reducing the bore as at 18 adjacent its upper end. The body of the guard member is concavo-convex and at its smaller face is provided with a cylindrical projection 19. This cylindrical

projection 19 extends upwardly into the reduced part of the bore between, or better, in the same plane with the annular shoulder 17. This arrangement serves to prevent a surface to be engaged by wires that might be of service in an attempt to refill the bottle but at the same time leaves enough space between the projection and shoulders to allow the contents of the bottle to readily 10 flow therefrom. A bead or flange 20 is formed on the periphery of the bottom portion and is curved upon its inner face so that wires inserted within the neck of the bottle will be deflected upwardly and thus 15 prevented being forced into position to engage the weight 9 so that it may be held away from the valve 13. The liquid will readily escape from the bottle when it is tilted so that the valve 9 moves from its 20 seat 8, through the openings in the seat 8, between the edge of the circular body portion of the member 9 and inner face of the neck 4 and through the reduced portion 25 18 of the neck 4. The arrangement of the frusto conical inner face 15 of the body portion of the guard member 14 facilitates the seating of the valve 9 when the bottle is tilted only slightly but does not interfere with the unseating of the valve 9 when 30 an appreciable tilt is given the bottle.

It will be apparent with reference to the foregoing description and accompanying drawings that there has been provided a non-refillable bottle which is capable of 35 performing all functions hereinbefore described in a reliable, efficient and expeditious manner. Further the device may be quickly secured to the bottle and is held against removal thus preventing the refilling of the bottle.

In reduction to practice, I have found that the form of my invention, illustrated in the drawings and referred to in the above

description, as the preferred embodiment is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:—

A non-refillable bottle comprising the combination with the neck of a bottle having a flange formed thereon, of a cylindrical neck member, said cylindrical member having one end enlarged and provided with an internal angular recess adapted to fit down on the flange of the neck of the bottle, an annular shoulder formed interiorly of the cylindrical neck member adjacent its upper open end, a valve seat upon the outer end of said bottle, a valve positioned upon said valve seat, a weight resting upon said valve, a guard member comprising a body portion of circular contour and provided with an inverted frusto-conical engaging head and having a plurality of spaced legs connected to and extending downwardly therefrom adapted to rest upon said valve seat to limit the outward movement of said weight and prevent the bottle from being refilled after once being emptied, the upper interior shoulder of the cylindrical member limiting the outward movement of said guard member when said bottle is held in a tilted position.

In testimony whereof I affix my signature in presence of two witnesses.

HARRY WOOD.
